[57] CLAIM

The ornamental design for a combined respirator and goggles, as shown and described.

DESCRIPTION

FIG. 1 is a front perspective view of a combined respirator and goggles showing my new design;

FIG. 2 is a front elevational view thereof;

FIG. 3 is a right side elevational view thereof, the left side elevational view being a mirror image of that shown; and

FIG. 4 is a top plan view thereof.

FIG. 1

FIG. 2

FIG. 3

FIG. 4
